(57) CLAIM

The ornamental design for a handle for a cosmetic brush, as shown and described.

DESCRIPTION

FIG. 1 is a front elevational view showing the design for a handle for a cosmetic brush.

FIG. 2 is a side elevational view showing the design for a handle for a cosmetic brush.

FIG. 3 is a front elevational view similar to FIG. 1, taken at an angle to one side, showing the design for a handle for a cosmetic brush.

FIG. 4 is a top end view of the design for a handle for a cosmetic brush; and,

FIG. 5 is a bottom end view of the design for a handle for a cosmetic brush.

The broken lines shown near the top of FIGS. 1, 2 and 3, and at the periphery of FIGS. 4 and 5, illustrate portions of the article that form no part of the claimed design.

The broken line shown at the center of FIG. 4 illustrates a boundary of the claimed design and forms no part thereof.
